MULTICHANNEL RADIO SYSTEM.

Application filed August 29, 1922. Serial No. 584,958.

This invention relates to systems for the transmission and reception of radiant energy and has for its object to provide improved methods and means for the transmission of intelligence by Hertzian waves whereby a message may be reliably received with a minimum of interference or blocking; to provide means for receiving a message over a plurality of channels having different characteristics independently thus effectually preventing blocking by malicious outsiders; and to provide methods and means for producing from different sources of energy a plurality of series of beats of the same frequency for controlling an indicating device, whereby any one of the series of beats may be employed for controlling the indicating device. Still other objects of the invention will appear from the following description taken in connection with the accompanying drawing.

The single figure of the drawing shows diagrammatically one form of receiving system embodying the invention.

In the drawing, there is shown so much of a so-called "wireless" receiving system as is necessary to an understanding of the invention. It is understood that the sending equipment (not shown) is adapted to impress upon the ether, a plurality of continuous waves all modulated at different frequencies but in a similar manner.

The illustrated system comprises a loop 10 and a second loop 11 arranged at right angles thereto, both loops being positioned at an angle of substantially 45° to the direction from which the radiant energy is expected to be received. The loop 10 forms part of a closed circuit 12 including an adjustable condenser 13 and resonant to a predetermined frequency. This frequency will be hereinafter represented by the symbol A.1. The circuit of the loop 10 is operatively connected to a three-electrode electron device 14 comprising a sealed container having therein a usual heated filament for emitting electrons, a plate 18 upon which the electrons impinge, and a grid 19 for controlling their passage. The grid is connected to the loop 10 so as to be controlled by electrical oscillations caused to be set up therein by electro-magnetic or so-called Hertzian waves.

The loop 11 forms part of a similar closed circuit 15 which includes an adjustable con-

denser 16 and is adjusted to be resonant to a second frequency A 2 differing from the first-named frequency A 1. The circuit of the loop 11 is similarly connected to the grid of a second three electrode electron device 17 having a usual heated filament, grid and plate.

The plate circuit of the device 14 includes a primary winding 20 of a transformer 21. Similarly, the plate circuit of the device 17 includes a primary winding 22 of a second transformer 23. A single battery of cells or other source of direct current such as a battery 24 may be provided for maintaining the anodes 18 of both devices 14 and 17 normally at a predetermined positive potential with respect to their filaments.

The secondary winding of each of the transformers 21 and 23 is included in an oscillatory circuit, such as 40 and 41 respectively, each including means for tuning the circuit, such as a variable condenser or the like, to be resonant to the respective modulating frequencies.

Each oscillatory circuit 40 and 41 includes a primary winding of a transformer, such as 50 and 51 respectively, the secondary windings of which form parts of closed oscillatory circuits 52 and 53 including adjustable condensers 54 and 55 respectively. The circuit 52 is operatively connected to a three-electrode electron device 56 and is arranged to act upon its grid 19 to control the output circuit of the plate 18 thereof. Similarly, the closed circuit 53 is operatively connected to the grid 19 of a corresponding thermionic device 57.

The plate circuits of the devices 56 and 57 include respectively windings 60 and 61 of a transformer 62. Inductively coupled to these windings is a tertiary winding 63 which is included in a resonant circuit 64 having, for example, a variable condenser 65 and a winding 66 of a coupling 67.

The coupling 67 is provided with a secondary winding 70 connected in circuit with the grid 19 of a thermionic device 71, having a usual heated filament. A tuning condenser 72 may be provided in a conventional manner. The output circuit of the device 71 may include a controlled device, such as a telephone receiver 73. The controlled device may, however, take the form of a solenoid or relay to control a movement or function of a body such as a torpedo, boat or other object.

A heterodyne shown conventionally as an alternator 80 and a transformer 81 acts on a conductor 82 included in the grid circuits of both devices 56 and 57.

- 5 Operation of the heterodyne 80 produces an alternating electro-motive force in the conductor 82 and, in co-operation with the oscillations induced in the secondary windings of the transformers 50 and 51, a plurality of series of beats, as will be subsequently set forth.

It is obvious that the tuning condensers 54, 55 and 72 may be omitted without seriously affecting the operation of the system.

- 10 15 In the operation of the system described, the sending station is constructed to impress upon the ether two series of continuous waves of different radio frequencies. The frequencies will be hereinafter designated 20 A 1 and A 2 respectively. The waves are modulated at the sending station by currents of frequencies (B 1 and B 2) less than their wave frequencies. The receiving loops 10 and 11 and the associated circuits 12 and 15 25 are tuned respectively to the frequencies, A 1 and A 2.

- The thermionic devices 14 and 17, acting as detectors, produce in their output circuits superimposed currents having frequencies 30 corresponding to the modulating frequencies employed at the sending station. The two resonant circuits 40 and 41, which are tuned respectively to these modulating frequencies, transmit currents of substantially these 35 frequencies only. The heterodyne 80, 81 is adjusted to produce an alternating electro-motive force having a frequency such that it produces equal beat frequencies with modulating frequencies B 1 and B 2. These 40 beats control the devices 56 and 57 respectively, and there are produced in the output circuits thereof, including the windings 60 and 61 of the transformer 62, superimposed currents of this last named beat frequency. 45 This beat current is induced into the circuit of the indicating device or magnet 73. Circuit 64 is resonant to the beat frequency. The electron device 71 may act as an amplifier when an alternating current device 50 such as a telephone receiver 73 is used or as a rectifier when the device 73 is a solenoid, or other direct current device.

- 55 While any desired frequencies may be employed which fulfill the above enumerated requirements, I will cite as examples which may be employed for telegraphic messages the following:

- A 1; 500,000 cycles per second.
A 2; 200,000 cycles per second.
60 B 1; 18,000 cycles per second.
B 2; 20,000 cycles per second.
Heterodyne 19,000 cycles per second.
Beat 1,000 cycles per second.
- Thus it will be seen that a message may be 65 transmitted by suitably modifying, as by in-

terrupting, or otherwise modulating the currents of frequencies, B 1 and B 2, these currents thus acting as so-called carriers. Since two independent carriers are employed, each producing independently a beat current, the 70 message appears in the output or indicating circuit, even though outside interference or other difficulty has rendered one of the channels temporarily inoperative.

If desired, in the use of the system the 75 message may be broken up into several illegible parts, each so chaotic that it cannot be understood. For example, if the message be telegraphic, the dots may be sent over one channel and the dashes over the other. 80 Illegitimate listening in would not then result in revealing the true message, as neither channel could be understood alone.

While I have shown and described one 85 of the forms in which the invention may be practiced, and given by way of example values for the frequencies which may be employed, it is to be understood that the scope of the invention is not to be determined thereby, reference being had to the 90 appended claims for that purpose. For example, the modulating frequencies, B 1 and B 2, may be equal: in the example cited B 1=20,000 cycles per second.

95 What is claimed is:

1. A system for the transmission of intelligence by radiant energy, comprising a plurality of channels for receiving the radiant energy independently of each other, said channels including a corresponding plurality of receiving devices tuned to frequencies differing from each other by a predetermined amount, and heterodyne means for producing with oscillations of said frequencies a plurality of series of beats of substantially equal frequencies. 100

2. A system for the transmission of intelligence by radiant energy, comprising a plurality of receiving channels selectively responsive to different portions of said energy, said channels including a corresponding plurality of receiving circuits tuned to frequencies differing from each other by a predetermined amount, heterodyne means for producing with oscillations set up in 110 said channels a plurality of series of beats of substantially equal frequencies, and an indicating device connected with said channels. 115

3. A system for the transmission of intelligence by radiant energy, comprising a plurality of channels for receiving a message independently of each other on a plurality of series of waves differing in a frequency characteristic, said channels including a corresponding plurality of receiving circuits tuned to different frequencies, and means for producing current of lower frequency from each of said series of waves, heterodyne means for producing with said 120

currents a corresponding plurality of series of beats of substantially equal frequencies, and an indicating device connected to said channels and responsive to oscillations having the frequency of said beats.

4. In a system for the transmission of a message through the ether, a plurality of channels for independently receiving a plurality of series of waves of different radio frequencies, said channels including receiving circuits exposed and responsive to the ether waves and tuned to their different frequencies respectively and means cooperatively associated with each of said circuits for producing current of lower frequency from the waves received thereby, and heterodyne means for producing with the respective currents a plurality of series of beats of substantially equal frequency.

5. In a system for the transmission of a message through the ether, a plurality of channels for independently receiving a message from the ether on a plurality of series of waves of different radio frequencies, each of said channels including a receiving circuit arranged to be responsive to ether waves and tuned to one of said different wave frequencies and means cooperatively associated with said circuit for producing current of lower frequency from the waves received thereby, heterodyne means for producing with said currents a corresponding plurality of series of beats of substantially equal frequencies, and an indicating device connected with said channels.

6. In a system for the transmission of a message through the ether, a plurality of channels for independently receiving the message from the ether on a plurality of series of waves differing in a frequency characteristic, said channels including means for producing currents of different frequencies from the respective series of waves and receiving circuits tuned to said different frequencies, means for producing with said currents a corresponding plurality of series of beats of substantially equal frequencies, a circuit selectively responsive to the frequency of said beats, and an indicating device controlled by said last-mentioned circuit.

7. In a system for the transmission of a message through the ether, a plurality of channels for independently receiving the message from the ether on a plurality of series of waves differing in a frequency characteristic, said channels including means for producing currents of different frequencies from the respective series of waves, heterodyne means for producing with said currents a corresponding plurality of series of beats of substantially equal frequencies an indicating device responsive to currents of the frequency of said beats, and means for selectively transmitting oscillations having

the frequency of said beats to said indicating device.

8. In a system for the transmission of a message through the ether, a plurality of channels for independently receiving the message from the ether on a plurality of series of waves differing in a frequency characteristic, said channels including means for producing currents of different frequencies from the respective series of waves, heterodyne means for producing with said currents a corresponding plurality of series of beats of substantially equal frequencies, and an indicating device responsive to currents of the frequency of said beats.

9. In a system for the transmission of a message through the ether, a plurality of differently tuned channels for independently receiving from the ether a plurality of series of high frequency waves modulated at different secondary frequencies, means in each of said channels for detecting the energy received thereby to produce current of the respective secondary frequency, heterodyne means for producing with the currents from said channels a corresponding plurality of series of beats of substantially equal frequencies, said means including a network independently coupled to each of said channels, and an indicating device connected with said network.

10. In a system for the transmission of a message through the ether, a plurality of channels for independently receiving from the ether a plurality of series of high frequency waves modulated at different secondary frequencies, means in each of the channels for detecting the energy received thereby to produce current of the respective secondary frequency, receiving circuits in the channels tuned to the secondary frequencies respectively, heterodyne means for producing with the currents from said channels a corresponding plurality of series of beats of substantially equal frequencies, and an indicating device connected with the channels.

11. In a system for the transmission of a message through the ether, a plurality of channels for independently receiving from the ether a plurality of series of waves of different radio frequencies, each modulated at a secondary frequency, circuits responsive to the waves included in said channels respectively and tuned to said different radio frequencies, means cooperatively associated with each of said circuits for detecting the energy received thereby to produce current of the corresponding secondary frequency, heterodyne means for producing with the currents from said channels a corresponding plurality of series of beats of substantially equal frequencies, and an indicating device connected to said producing means and said channels.

12. In a system for the transmission of a message through the ether, a plurality of channels for independently receiving from the ether a plurality of series of waves of different wave frequencies modulated at different secondary frequencies respectively, a plurality of circuits included in each of said channels and tuned respectively to one of said wave frequencies and one of said secondary frequencies, means in each of said channels between said circuits for detecting the energy received thereby to produce current of the corresponding secondary frequency, heterodyne means for producing with the currents from said channels a corresponding plurality of series of beats of substantially equal frequencies, and an indicating device connected to said producing means and said channels.
13. In a system for the transmission of a message through the ether on a plurality of series of waves, a receiving arrangement comprising a plurality of independent channels including differently tuned circuits, an indicating device, and means for transmitting current from said channels to the indicating device, said means comprising a heterodyne for converting currents from said channels into audio frequency currents of substantially equal frequencies.
14. In a system for the transmission of a message through the ether on a plurality of series of waves, a receiving arrangement comprising a plurality of independent channels including differently tuned circuits, an indicating device and means for transmitting current from said channels to the indicating device, said means comprising a heterodyne for converting currents from said channels into audio frequency currents of substantially equal frequencies and an oscillatory circuit tuned to said last-mentioned frequency.
15. A method of communicating a message by radiant energy which consists in transmitting a plurality of series of high frequency waves modulated in accordance with the message, receiving said plurality of series of waves in separate receiving channels, producing in said receiving channels from said plurality of series of waves a corresponding plurality of series of currents of different frequencies respectively, heterodyning said currents to produce therefrom a plurality of series of beats of substantially equal frequencies and controlling a single indicating device by said plurality of series of beats.
16. A method of communication by radiant energy which consists in transmitting a plurality of series of high frequency waves of different wave frequencies having periodic variations of different frequencies respectively and all modulated in accordance with the message, receiving the plurality of series of waves in different receiving channels, detecting the series of waves in the respective receiving channels to produce currents having the frequencies of the variations respectively, heterodyning said currents to produce a plurality of series of beats of substantially equal frequencies, and controlling a single indicating device by said plurality of series of beats.
17. The method of communicating a message by radiant energy which consists in transmitting two series of high frequency waves, each modulated in accordance with the entire message, receiving the two series of waves in differently tuned receiving channels, producing in said channels two currents modulated in accordance with the modulations of the transmitted waves, heterodyning the currents to produce two series of beats of substantially equal frequencies and impressing both of said series of beats on a common indicating device.
- In testimony whereof I hereunto affixed my signature.
- EMORY LEON CHAFFEE.
